UNITED STATES PATENT OFFICE.

JAMES M. O'NEALL, OF ST. LOUIS, MISSOURI.

AIR-SHIP.

No. 826,052.

Specification of Letters Patent.

Patented July 17, 1906.

Application filed January 9, 1905. Serial No. 240,261.

To all whom it may concern:

Be it known that I, JAMES M. O'NEALL, a citizen of the United States, and a resident of St. Louis, Missouri, have invented certain new and useful Improvements in Air-Ships, of which the following is a specification containing a full, clear, and exact description, reference being had to the accompanying drawings, forming a part hereof.

10 My invention relates to improvements in air-ships; and it consists of the novel construction hereinafter specified and claimed.

The object of my invention is to provide an improved air-ship which shall possess 15 greater dirigibility than those heretofore constructed.

A further object of my invention is to provide an improved air-ship which shall have great power and offer less than the usual 20 amount of resistance to the air in its passage therethrough.

In the drawings, Figure 1 is a side elevation of an air-ship embodying my invention. Fig. 2 is a sectional elevation of the rear end 25 of the propeller-tube and adjacent connections. Fig. 3 is a sectional front end view taken on the line 3 3 of Fig. 1. Fig. 4 is a sectional rear view taken on the line 4 4 of Fig. 2. Fig. 5 is a detail view in perspective 30 of one of the screw or propeller blades. Fig. 6 is a detail plan view of the rudder and its connections.

In carrying out my invention I may make use of any one of a series of constructions 35 which are mechanical equivalents, one of which is shown in the drawings.

7 indicates a balloon which is substantially conical in form and normally located in horizontal position with its pointed end at 40 the front of the machine, and the rear end of said balloon is rounded rather abruptly and is substantially semispherical shaped. The balloon may of course be made of any suitable material heretofore used for the purpose, 45 and it is arranged to support the driving and steering devices, which are suspended beneath said balloon by means of common cords or ropes 8, the upper ends of which are connected to a common balloon-netting 9, 50 and the lower ends of which cords or ropes are connected to the frame of the driving and steering mechanism.

10 indicates a pneumatic tube which extends beneath and substantially parallel with 55 the balloon. At the rear end of said tube is a housing or enlargement 11, the interior of

which connects with the interior of said tube, and a suitable screw or propeller 12 is mounted within said housing, and the propeller is fixed upon a shaft 13, which has proper bearings 14. Said propeller in the present instance is provided with four arms 15, which project from a common hub, and said arms are fitted with paddles or vanes 16, one edge and one end of which are provided with connecting-flanges 17, and said paddles or vanes are of course at an angle for an obvious purpose. Mounted above the pneumatic tube 10 upon the frame 18 is a suitable motor 19, which is connected to the propeller-shaft 13 by means of pulleys 20 and 21 and a belt 22. In this connection I point out the fact that said pulleys and belt may be replaced by common sprocket-wheels and a chain. 23 indicates an additional propeller, which is mounted beneath the forward portion of the pneumatic tube 10 to rotate in a horizontal plane, and this propeller is driven by a horizontal shaft 24, which extends beneath the pneumatic tube and is connected to the propeller by 70 means of common gear-wheels 25. Motion is communicated to said shaft 24 by means of the pulley 26, fixed upon said shaft, a belt 27, and a pulley 28, fixed upon the shaft 13 of the first-mentioned propeller. It is 75 needless to say that such means for driving the shaft 24 and its propeller may be supplanted by common sprocket-wheels and chain or by any other common mechanical equivalent thereof.

Beneath the pneumatic tube 10 are suitable supporting-wheels 29, which, with their axles 30, constitute a sort of truck upon which the air-ship may rest and be moved from place to place on the ground. In some 90 cases I may provide a long shallow boat in the form of an aeroplane, which is hollow and constructed gas-tight in such a manner that it may be filled with gas to assist in lifting the air-ship, whether the boat be moving 95 through the air or upon the surface of the water. This boat is shown in dotted lines in Fig. 1 and indicated by the numeral 31. In case the boat 31 is used it will also be necessary to enlarge the diameter of the wheels 29, 100 as indicated by dotted lines. If the motor is what is known as a "gasolene-motor," it may be supplied with fuel from a gasolene-tank 32, which is supported upon the frame 18.

33 indicates a platform adjacent the motor 110 19, which is provided for the accommodation of the operator.

34 indicates a rudder, which is pivotally mounted in a vertical position in a fork 35 and connected thereto by means of a pivot or pin 36, so that said rudder may be oscillated 5 in a vertical plane, as indicated by the dotted lines in Fig. 2. Said rudder is also capable of lateral oscillation by reason of its fork 35 being pivotally connected to the cross-bar 37 by means of a pivot 38. Upon each side of 10 the rudder 34 are aeroplanes 39, which move with said rudder.

For the purpose of controlling the rudder I provide a hand-lever 40, which is pivotally connected intermediate of its ends to a 15 rocking cross-bar 41 by means of a bolt or pin 42. The forward end of said hand-lever extends above the operator's platform 33, and the rear portion of the hand-lever extends to a point above said rudder 34, and 20 the rudder is connected to said hand-lever by means of an oscillating and sliding rod 43, the lower end of which rod is pivotally connected to the forward end of said rudder by means of a bolt or pin 44. The said sliding rod 43 is 25 loosely mounted in a bearing 45 and located centrally of the length of a fixed cross-bar 46, and said bearing also acts as a fulcrum for the oscillating and sliding rod 43 whenever the latter is used as a lever. The upper end of 30 said oscillating and sliding rod 43 is connected to the hand-lever 40 by means of a common eyebolt 47. It will be observed that the rudder 34 is located directly in the rear of the pneumatic tube.

35 The operation is as follows: The balloon 7 should first be inflated to afford the necessary buoyancy and then the motor 19 set in motion and the rudder placed in the position in which it is shown in solid lines. The air- 40 ship should now be permitted to ascend a slight distance, and the power or motion imparted to the propeller 12 will cause the ship to move forward and a current of air will be drawn in the front end of the pneumatic tube 45 10 and discharged at the rear end thereof through the housing 11 and will be more or less discharged upon the rudder 34 and the aeroplanes 39, carried by said rudder. The operator may of course regulate the speed 50 and power of the motor by means of the common regulating appliances with which all motors are provided, so that the forward speed will be greater or less or the ship may be brought to rest. The front propeller 23 is 55 what I term the "altitudinous" controller, as by its rotation the air-ship is caused to ascend, and by reversal of its movement the air-ship is caused to descend. The reversal of said propeller 23 is accomplished by the 60 common reversing-gear used upon automobiles. Said propeller 23 may even be started and controlled by tightening and loosening the belt 27 while the motor 19 continues in operation. The reversal of the power of the 65 motor 19 would also cause a reversal of the

driving-propeller 12, and thereby move the air-ship backward or at least act as a brake to bring the same to a standstill during its forward flight. The altitude of the air-ship may also be controlled by moving the rudder 70 34 and the aeroplanes 39, connected therewith, which may be accomplished by means of the hand-lever 40, and by tilting the hand-lever to the position in which it is shown in dotted lines in Fig. 2, the blast of air from the pneumatic tube will strike the said aeroplanes and cause the rear of the air-ship to be depressed. Depressing the rear of the air-ship in the manner just described would cause the pneumatic tube and other parts to 80 act as aeroplanes and the entire ship will be compelled to ascend. Placing the rudder and aeroplanes in a position the reverse of that in which they are indicated by dotted lines in Fig. 2 will have the opposite effect 85 upon the entire air-ship. Placing the rudder in a position in which it is indicated by dotted lines in Fig. 6 will cause the rear end of the air-ship to move toward the right hand and the entire ship to move forward in a direction 90 toward the left hand. Reversing the position of the rudder will cause a corresponding change in the direction of the air-ship.

From the above it will be seen that the air-ship is under perfect control and may be 95 caused to move in any desired direction, either to the right, left, up, or down. I combine the aeroplane and the balloon and eschew the uncovered screw or fan propellers, which handle the atmosphere in all directions at a 100 loss of speed and power. I use the aeroplane for controlling the ship, and the balloon is used only to suspend the action of gravity. The pointed end of the balloon permits the same to move through the air with small 105 resistance, as it is moving into a vacuum produced by the tube, while the air which would otherwise oppose the forward movement of the pneumatic tube is actually drawn within said tube and expelled at the rear of the machine, thus doing away with a great amount 110 of air resistance at the front of the machine. By incasing the propeller 12 I cause the air to be discharged violently by centrifugal motion and compel the same to be discharged 115 rearwardly. This action is augmented by the flanges 17 of the paddles 16.

It is obvious that I may use any desired shape of balloon and also any desired shape of pneumatic tube, and, in fact, I may use 120 what is known as a "multiform" tube, consisting of a number of small tubes, as indicated by the dotted lines in Fig. 3.

What I claim is—

1. In an air-ship, a gas-bag, a tube suspended and held horizontally beneath said gas-bag, there being an enlarged chamber formed at the rear end of the tube, a fan vertically arranged and held for rotation in said chamber, a motor positioned on top of the 130

tube for driving the fan, a rudder having horizontal and vertical blades hung for vertical and horizontal movement immediately back of the fan, a hand-lever connected to the forward end of the lever for manipulating the same, a fan arranged beneath the forward portion of the tube, and a driving connection from the first-mentioned fan-shaft to said last-mentioned fan; substantially as specified.

10

2. In an air-ship, a gas-bag, a tube suspended and held horizontally beneath said gas-bag, there being an enlarged chamber in the rear end of said tube, a fan vertically arranged and held for rotation in said chamber, a motor for said fan, a frame extending rear-

wardly from the top of the tube, a fork pivotally held in said frame and depending therefrom, a rudder having horizontal and vertical blades of equal area suspended in the yoke, and an operating-handle connected to the forward end of said rudder for moving the same vertically and horizontally; substantially as specified.

15

In testimony whereof I have signed my name to this specification in presence of two subscribing witnesses.

JAMES M. O'NEALL.
